DISCHARGE DEVICE

Hans J. Spanner and Werner Lucas, Berlin, Germany; said Spanner assignor of his right to General Electric Company, a corporation of New York

Application October 23, 1936, Serial No. 107,191
In Germany November 21, 1931

17 Claims. (CL 176—122)

This invention relates to electrical discharge devices. More particularly the invention relates to such devices adapted for standardized production and commercial use under varying conditions such, for example, as those encountered in general illumination service, or for ultra violet radiation burners.

In prior applications of Hans J. Spanner alone and in conjunction with others particularly Serial No. 351,368, filed March 30, 1929, Serial No. 387,986, filed August 23, 1929, Serial Nos. 397,427, 397,428 and 397,429 all filed October 4, 1929, Serial No. 400,805, filed October 19, 1929, Serial No. 558,148, filed August 19, 1931, Serial No. 643,502, filed November 19, 1932, Serial No. 714,949, filed March 10, 1934, Serial No. 744,206, filed September 15, 1934 and Serial No. 51,390, filed September 25, 1935 and in the applications of Edmund Germer, Serial No. 500,346, filed December 15, 1930 and Serial No. 60,774, filed January 25, 1936, and in the applications filed herewith, there have been described and claimed a type of discharge device adapted particularly for illuminating lamps and ultra violet burners for operation from ordinary low voltage distribution line, and various improvements and special features of such devices.

These inventions and improvements disclosed in the said prior applications have made practicable the design of high efficiency discharge devices especially for illumination and ultra violet purposes which may be adapted to widely varying conditions and requirements.

It is an object of the present invention to so improve upon such devices that they may be manufactured in standard designs and sold for general purposes and use under varying conditions.

Another object of the invention is to provide devices of this character adapted to utilization in standard outlet sockets and connectors without injury to such sockets and connectors or impairment of the efficiency of the discharge device. Another object of the invention is to assure the quick-starting of such devices even without the necessity for extraneous starting devices in the circuits by which the devices are operated.

Another object of the invention is to provide a device capable of burning in horizontal as well as in vertical position without serious injury to the walls of the device.

Another object of the invention is to provide such a device in which all delicate and dangerous parts of the lamp are enclosed so as to avoid

danger from handling to which the devices would be subjected in transportation and use.

In the accompanying drawings we have shown, and in the following specification have described 5 a preferred embodiment of our invention by which these objects are achieved together with various modifications thereof and alternatives. It is to be understood, however, that the drawings and descriptions are not intended to be exhaustive 10 nor limiting of the invention, but on the contrary are given for the purposes of explaining and illustrating the invention and the best ways of embodying it in practical construction, and of explaining the principles of the invention so clearly 15 that others skilled in the art may, without difficulty, embody the invention in numerous other forms each as may be best suited to the conditions and requirements of a particular use.

In the drawings:
20 Fig. 1 is a view in longitudinal section of a lamp embodying our invention;

Fig. 2 is a view similar to Fig. 1, but of a modified form of the lamp;

Fig. 3 is a view in cross-section through a tube 25 similar to those illustrated in Figs. 1 and 2 showing an electrode mounting;

Fig. 4 is a plan view of the electrode and its mounting as used in the embodiments shown in Figs. 1 and 2.

30 Fig. 5 is a view in side elevation of another embodiment of our invention;

Figs. 6 and 7 are views in longitudinal and cross-section respectively on a greatly enlarged scale of a control switch adapted for use with a

35 lamp as shown, for example, in Figs. 1, 2, 5 or 8;

Fig. 8 is a view in axial section of another lamp embodying our invention; and

Fig. 9 is a diagrammatic view of a circuit 40 adapted to assure starting of the lamps on low voltage lines.

Referring specifically to Figs. 1 and 2, we have shown there two forms of tubes adapted for general illumination purposes and for operation from a 110-120 volt line with an operating current of

45 about 5 amperes immediately after starting and reducing, with evaporation of mercury or other vaporizable materials, to a current of about 3.4 amperes during normal operation. Fig. 2 shows in approximately full scale a lamp adapted for operation, e. g., from 110 volt-150 volt supply. In Fig. 1, accurate scale representation has been

50 sacrificed to permit clearer representation of the parts.

The electrodes 11 used in these tubes are shown 55 specifically in Fig. 4. These may consist, for ex-

ample, of about 40 wires of about 0.25 millimeter diameter, e. g., of pure nickel or tungsten, tightly twisted or interwoven into a stranded wire which is in turn wound into three tight coils as shown. These coils constitute the electrode proper 11, which, after suitable activation serves to carry the discharge.

In the activating treatment of the electrodes during the manufacture of a lamp care should be taken to see that pure emissive metal or other product which emits electrons while cold is formed at the surface of the electrode by reduction of the barium oxide or other activating material, but there should also remain in the porous structure of the electrode some of the activating material which is not completely reduced, e. g., barium oxide which is partially reduced to a sub-oxide or barium which is in intimate combination with the metal of the supporting structure, e. g., nickel or tungsten. To effect this result the supporting metal structure may be covered and impregnated with the activation material, and the electrode, after being sealed into the tube, subjected to a high temperature treatment near the melting point of nickel and eventually to a treatment by direct action of the discharge, e. g., in an inert gas or mercury vapor, until the desired reduction is attained. This treatment is not a part of the present invention, but is more fully described and claimed in our co-pending applications and, therefore, need not be further elaborated upon here.

A second important consideration in the starting of these lamps is the provision of a gaseous filling at suitable pressure. This also is a distinct invention described and claimed in a co-pending application. In a tube of the form and dimensions shown, and designed for operation from 110 to 150 volt lines, this gas filling may consist of argon at a pressure of about 8 to 14 millimeters mercury column.

These electrodes, which are adapted to become incandescent by action of the discharge without any additional heating means are not claimed per se in the present application and are more fully described and claimed in our co-pending applications. These electrodes, however, although not essential to the present invention in its broadest aspect, are particularly advantageous because they eliminate the necessity for special heater connections and make possible a simple and rugged construction more suitable for the standardized production and commercial use, which is one object of this application.

In use with alternating current, preferably at least two such electrodes are fitted in the tube, and they alternately become cathode and anode. When direct current is used only one electrode of such self-heating type is necessary and the anode as is well understood can be made of non-disintegrating material. It is advantageous with direct current to make the anode of larger dimensions than the cathode.

The ends of the coils constituting the electrode 11 are welded to the short-circuiting bow 12, which is made of a single piece of refractory metal, such as nickel or tungsten, heavy enough to support the electrode from the lead-in wire and to carry the induced currents resulting from the high frequency bombardment used to produce the activation of the electrodes, without excessive resistance or overheating in the bow 12 itself. For example, this bow 12 may be made of nickel wire 3 millimeters in diameter flattened

to a thickness of about 1½ millimeters. The ends of the bow are welded to the ends of the wires in the electrodes proper 11 in order to give good electrical contact and mechanical support.

The bow 12 is also welded to the lead-in or support wire 13 or 14 at the side opposite to the electrode proper.

Before being sealed in, the emitting part 11 of the electrode is covered with the activation material, e. g., a layer of finely ground barium oxide advantageously mixed with other refractory oxides, e. g., calcium oxide, beryllium oxide, magnesium oxide, zirconium oxide, etc., made into a viscous mass with distilled water. This mass is worked into the interstices of the electrodes and the electrodes when thus treated are preferably kept away from contact with air until sealed into the tube 15.

Although the particular construction shown is not essential to certain features of our invention in their broad aspect, we have found it very advantageous to mount one of the electrodes on a wire 13 which is adapted to carry the discharge current to the electrode and is sufficiently long to extend from the electrode to the opposite end of the tube and out through the wall of the tube, to which it is sealed as shown in the drawings. In order to avoid any danger of this wire short-circuiting the discharge, it is advantageously insulated throughout its length, e. g., by a glass tube 16 which is fused at one end to the wall of the tube 15 and extends along the wire 13 substantially to its electrode.

In the case illustrated in Fig. 1, a second support wire 17 also welded to the bow 12 extends beyond the electrode to the end of the tube 15 where it engages in a depression 18 in the wall of the tube and preferably is held by fusion of the glass wall of the tube thereto.

The wire 17 may be omitted, as shown for example in Fig. 2, and the entire stress of supporting the electrodes carried directly by the wire 13 and its surrounding tube 16; or, as shown in Fig. 3, the bow 12a may be designed substantially to fit within the end of the tube 15; and in this case the bow 12a is preferably resilient so as to press against the walls of the tube and thereby to support itself and the electrode 11 directly against the tube. It is not essential, however, that the bow 12a be directly in contact with the tube, and it may be made substantially rigid and spaced from the tube so as to allow for differences in thermal expansion, but sufficiently close to avoid any danger of crashing against the side of the tube.

The electrode support wire 14 need not be insulated and may pass directly from the seal to the bow 12 as shown, for example, in the drawings.

As shown in the drawings, the glass tube 16 carries a metal band 19 which is in a capacitative relation to the lead wire 13, but is insulated therefrom by the dielectric tube 18. This metal band 19, or the band 19a in Fig. 2, has a part extended near the lower electrode 11 to provide an auxiliary electrode for an initial capacitative or corona discharge. In the case illustrated in Fig. 1, this auxiliary electrode consists of a band of wire mesh 20 surrounding the insulating tube 18 and extending toward the electrode 11. This auxiliary electrode is connected to the band 19 by a metal strip 21 which is integral with the band 19 and is welded to the mesh 20.

In the embodiment illustrated in Fig. 2, a similar function is served by the integral portion 20a

turned back from the band 19a. Capacity between the electrodes may also be provided by a strip on the outside of the tube. This may be in addition to or instead of the capacity members already described inside of the tube, particularly in the case where the connection to the upper electrode is sealed through the upper end of the tube and brought back on the outside of the tube instead of the inside as shown. In the drawings we have shown such a capacity member as a conductive film 22, e. g., of reflecting metal; and in order that this may come as close as possible to the electrode and also that the temperature in the end of the tube 15 may remain as high as possible, the tube 15 around the electrode is made smaller than the principal portion of the tube in which the luminous arc burns.

In the case shown in Fig. 2, the layer 22 is connected to the lead wire 13 for the electrode at the opposite end of the tube so that a capacitative discharge may occur between the electrode 11 and the side of the tube in parallel to that between the electrodes 11 and 20a. This capacity furthermore, in conjunction with a choke coil, such as is commonly used in series with such lamps to ballast the discharge, results in a better starting impulse and a more certain starting from the low voltage electrical supply line.

In the case illustrated in Fig. 1, the layer 22 is connected to the adjacent electrode, and in this case the capacity is between the layer 22 and the surrounding metal sleeve 23, which will be more fully discussed later. In this case the capacity is in parallel with the discharge and its effect is primarily that of improving the starting impulse especially in conjunction with a reactance, as already referred to.

A starting gas, e. g., one of the rare gases at a pressure near or above its pressure of minimum breakdown potential, and advantageously also a vaporizable material are provided within the tube 15. The vaporizable material is advantageously supplied in amount measured to produce, when completely evaporated, a vapor pressure such that the voltage which, in the first moment after starting has dropped to a very low value, is again increased almost to the starting voltage or even above; and the discharge, which in the first moments after starting is diffuse and substantially fills the interior of the tube, is constricted into an intense luminous cord very much narrower than the diameter of the tube. It is of great importance for the formation of the desired vapor pressure, especially in lighting tubes filled with metal which vaporizes only with difficulty, e. g., cadmium, sodium, and/or zinc, that the tube and especially the electrode end of the tube should be so made that there will be no places below the condensation temperature of the metals at their operating pressures and advantageously no places at much below the mean temperature of the interior of the tube.

The shape of the tube 15 shown in the drawings is well adapted to accomplish these results. The glass used in this tube may be any which is permeable to the desired radiation, which is sufficiently refractory to withstand the temperatures to which it is exposed from the arc, and which can be sealed, either directly or through intermediate sealing compounds, e. g., other glasses to the lead-in wires 13 and 14, or it may be silica. We have found that the hard borosilicate glasses, e. g., that known as Pyrex made by Corning Glass Works and sold under the designation 702P and the glass known as Uviol glass made

by Schott of Jena, are suitable for this purpose and can be sealed directly to a tungsten wire used for the lead-in wires 13 and 14.

The conductive layer 22 on the end of the tube 5 may be made by applying a colloidal suspension of graphite and water directly on the glass, e. g., the so called aquadag, and over this may be applied metal leaf or foil or an electro-deposit of metal. The conductive layer thus formed is carried down over the projecting seal to one of the 10 lead-in wires 13, 14.

An electrical and thermal insulating layer 24, 15 preferably of asbestos or other resilient compressible material adapted to serve also as a cushion between the metal sleeve 23 and the end of the tube 15, is provided over the reflecting conductive layer 22; and thus a condenser is established between the layer 22 and the metal sleeve 23 in parallel with the discharge. This capacity in the structure of the tube, with or without additional capacity, and especially when combined with a reactance, such as a choke coil in series, assists greatly in starting the lamp and operation on A. C. supply; and this is particularly the case if the capacity and the ballasting device are proportioned so that resonance, especially overbalancing or oscillation resonances ("Kippresonancen") as from relaxation oscillations, are formed with the alternating current supply. We have found, however, that continued resonance is undesirable in the operation of the tube; and if an additional capacity is used to give resonance, it should be switched into the circuit only for starting and switched off again 35 as soon as the discharge is started.

It is an advantage of the relaxation oscillations that they are particularly rich in harmonics, both above and below the frequency of the supply line, and thus resonance is easily produced without excessively large condensers. Furthermore, such resonance, being dependent upon the oscillations produced by the intermittent discharge, ceases 40 as soon as the main discharge is established and, therefore, with a properly designed circuit, extraneous switching devices are unnecessary.

An auxiliary discharge, e. g., to the auxiliary electrode 20 or to the wall of the tube 15 beneath the capacity layer 22 or to a resistance connected auxiliary electrode can be used in connection with the production of oscillations, and the additional capacity provided by the layer 22 and the sleeve 23 and/or between the layer 22 and the electrode 11 may serve at least in part as the parallel capacity. The capacity connected 45 auxiliary electrode combines particularly well with a relaxation oscillation circuit which is resonant to higher frequencies because such frequencies pass with less impedance through the capacitative auxiliary circuit and more readily 50 ionize the gas.

In Fig. 9, is shown diagrammatically a circuit 55 adapted to start the discharge by a resonance effect. The discharge tube is indicated at 15c and its electrodes at 11c. An auxiliary electrode 60 is indicated at 20c and connected to the lead wire 14c through an impedance 19c, which may be resistance or capacitance or even inductance, but this auxiliary is not essential. A ballasting impedance 55 is shown as an inductance, and a condenser 56 is connected in parallel across the electrodes forming a capacitative shunt around the discharge path, a relay 57 in this shunt is 65 adapted to be opened by the discharge current so as to disconnect the condenser.

70 In this circuit the condenser may be propor-

tioned with respect to the rest of the circuit so as to produce resonance at the frequency of the A. C. supply voltage or the circuit may be designed to give relaxation oscillations and to be resonant to a higher harmonic of the supply voltage which is produced by the relaxation oscillation resonance in the circuit, but as soon as starting occurs the shunt is opened by the relay 57 and thus the tube 15 is protected against the deteriorating effect of prolonged resonance.

For actual technical use it is of advantage to fit the lighting tubes in sockets adapted for standard incandescent lamps or so-called strip lamps (soffit lamps). With this end in view we have shown in Fig. 1 a lamp connected to a base 25 of standard Ediswan design; and, in order that this base 25 will not be overheated by the lamp, or vice versa will not excessively cool the end of the lamp, I have provided between the base 25 and the tube 15 a sleeve 23 which at one end is secured to the shell of the base 25 and at the other end is secured to the end of the tube 15. In the example shown this sleeve is of metal integral with or welded or soldered to the base and secured to the tube 15 by being crimped thereover and clamped by means of the wires 26 and 27. Holes 28 and 29 arranged in circumferential series and staggered with respect to one another form a thermal barrier to resist the transfer of heat from the tube 15 to the base 25. This sleeve 23 also surrounds and serves to protect the electrical connections 31 and 32 from the lead wires 13 and 14 respectively to the base.

Although we have referred particularly to the capacity effect between the shell 23 and the conductive layer 22, as shown in Fig. 1, this relationship is not essential to my invention in its broader aspects; and, for example in the case illustrated in Fig. 2, the shell is applied directly to the layer 22; or the layer 22 may be omitted entirely; and the sleeve 23 obviously could be made of insulating material instead of conducting material. Thus, for example, if this tube were of glass it could be fused directly to the glass of the envelope 15.

In the use of the device, the tube with its base 25 may be screwed into an ordinary Ediswan socket connected in series with a suitable ballasting device, e. g., a choke coil or high reactance or current limiting transformer, from a current supply line, e. g., at 110 volts.

Upon closing the circuit, a voltage is impressed upon the discharge path between the electrodes 11 and also, through the capacity 13, 19 and the electrode 20, is impressed upon the shorter path between the auxiliary electrode 20 and the adjacent principal electrode 11. Between these two, a capacitative or corona discharge may occur, which serves to ionize the gas, while the charge imposed upon the capacity member 19 or the current lead wire 13 serves to eliminate any static charge in the path between the main electrodes which otherwise might throttle or block the passage of the discharge. Accordingly, as soon as the gas is sufficiently ionized the discharge begins between the principal electrodes. At first this discharge occurs as a glow-discharge between cold electrodes. Almost at once, however, the fine wires of which the electrode is made begin to be heated by the discharge; and as they reach a glowing temperature the discharge is converted into an arc. With this arc burning in the low pressure atmosphere existing at that time within the tube 15, there is a minimum voltage drop in the lamp, e. g., of around

15 to 20 volts, and consequently a maximum current, e. g., of around 5 amperes. With this heavy loading, the tube is quickly heated until the mercury or other vaporizable supply is evaporated.

During this period the voltage drop in the tube increases, due to the increase in pressure by evaporation of mercury and/or other metal, until, during normal operation, the lamp burns with a voltage between the electrodes of 65 v. and a current of 3.4 amperes. In this final condition the arc appears as an intense luminous cord extending between the electrodes and of diameter very much less than that of the tube.

The heat of this luminous cord is so intense that if it were to impinge upon the wall of the tube 15 or upon the insulating tube 16 they might be quickly destroyed, or at least so far softened as to cause a failure of the lamp. With the lamp burning in vertical position, the danger of the arc cord impinging upon the wall is relatively slight; but if the lamp is burned in horizontal position, convection currents within the lamp tend to draw it upward into an arcuate form between the electrodes. The construction of the lamp, as shown especially in Fig. 2, is designed to correct this tendency. In this case, as will be observed from the drawing, the electrodes 11 are positioned substantially eccentrically of the tube and on the opposite side of the axis of the tube from the current lead wire 13; and furthermore the central portion of the tube is of enlarged diameter such that any bending of the arc which may occur can be accommodated without injury to the tube.

When the lamp is burned in horizontal position with the lead wire 13 uppermost the convection currents in the lamp still tend to lift the arc toward the upper wall of the tube, but this tendency is opposed by the repulsion resulting from the opposite magnetic effects induced around the current flowing through the wire 13 and the current flowing through the arc itself; and thus the arc is driven back downward against the force of the convection current. Even this, however, might be insufficient in a tube of small diameter. We have, therefore, increased the diameter near the center of the tube, shown in the drawing, which permits the arc to rise above the level of the electrodes without impinging upon the parts which might be damaged thereby.

Merely to increase the diameter of the tube, however, would, if the electrodes were at the axis, result in an excessive heat loss due to the increased area of the tube. In the present lamp, therefore, the electrodes are placed on the opposite side of the axis of the tube from the lead wire 16, and thus ample space is provided for the arc to rise above the electrodes without injuring any part of the tube.

When the lamp burns in vertical position, the opposed magnetic effect may cause it to assume some curvature toward the opposite side, but this effect decreases rapidly with the distance between the arc and the wire 13, and the curvature will be less than can be accommodated by the expansion in the diameter of the tube near its center. Thus the lamp as shown is capable of burning either in horizontal or vertical position.

It is important from this point of view also that the lamp is designed for operation from 110 volt supply line. As the voltage on the arc is increased the current loading for the same wattage lamp is, of course, decreased; and, since the magnetic effects are dependent upon the current, there is a decrease in the tendency of the lead

wire 13 to repel the arc. Similarly also, unless the final vapor pressure in the lamp is increased, the distance between the electrodes would have to be increased with increased voltage; and this in turn would increase the height to which the arc would rise with a given curvature. It is important, therefore, to keep the lamp as short as possible and the current of the arc as heavy as possible.

It will be readily understood from general principles of electromagnetism that the magnetic effect can be increased by increasing the number of longitudinal turns of the current lead wire around the lamp. In general, however, it is not desirable to rely too greatly upon the electro-magnetic effect, since with the lamp in upright position the electro-magnetic opposition on the one side and attraction on the other side might draw the arc against the opposite wall. It is preferable, therefore, to combine the partial correction by the electro-magnetic effect of the lead wire with the enlarging of the arc portion of the tube and the eccentricity of the electrodes, as shown particularly in Fig. 2.

Since the several features, of magnetic repulsion, eccentric positioning of the electrodes and the relation of the distance between the electrodes to the distance of their common axis from the upper wall of the tube, cooperate to produce the desired positioning of the constricted luminous cord of the arc, the extent to which each of these expedients is used will depend, to some extent at least upon the extent to which the others are utilized. In general, however, it may be said that for lamps of ordinary size, e. g., from 100 to 500 watts, a ratio of distance between the electrodes to the distance between their common axis and the upper wall of the tube, should be less than 10 and preferably less than 5, the greater values being permissible where more highly refractory glass or silica is used or where stronger magnetic repulsion is used, and the lesser values being required where magnetic repulsion is not used or where the current loading is small or the lead wire 13 is outside of the tube 15, and especially if it is at a substantial distance from the wall of the tube. Similarly, except for the higher wattages and with the current lead positioned so as to give strong magnetic repulsion, it is ordinarily more satisfactory to use less than 150 volts for such lamps which are to be burned in horizontal position; and, since for reasons of operation and particularly starting it is ordinarily necessary that the arc voltage should be at least about 75 volts, I prefer to use a lamp designed for operation direct from a 110 volt commercial supply line, e. g., with a choke coil in series.

The wattage of the lamp is important both because it determines to some extent at least the area of the tube and therefore its diameter, and also because with greater wattage there is greater heating in the arc and therefore more tendency for it to arch up due to convection currents.

Inasmuch as such a lamp when burned in horizontal position should have the lead wire from the outer electrode at the top of the tube, it is advantageous to have some provisions for assuring this position. This may be done by using an unsymmetrical connector base; or, with an Ediswan base as shown in the drawings, a mercury switch, e. g., as shown in Figs. 6 and 7 will protect against improper operation. The mercury switch there shown is designed to be mounted within the sleeve 23 or the base 25 or

otherwise suitably attached to the lamp so that it will always remain in the same relation to the tube 15. This switch comprises a tube 40 of glass or other insulating material having two contact wires sealed through one end, e. g., by the press seal 41, and extending to the opposite end as shown in Fig. 6. Each of the ends 42 and 43 form cups into which the mercury supply 44 within the tube may collect around the contact wires 45 and 46. Between the ends 42 and 43 the wires extend close to the bottom of the tube 40, e. g., as shown in Fig. 7. The tube 40 is oriented to the tube 15 with ends 4 and 43 pointed in the same directions as the ends of the tube 15 and the wires 45 and 46 lying along the side opposite to the side of the tube 15 along which the lead wire 13 passes. Thus if the tube 15 is positioned in upright position regardless of which end is uppermost the circuit of the lamp will be closed by the mercury pool lying in one end of the tube between the contact wires 45 and 46. Similarly, if the tube is in horizontal position with the lead wire 13 uppermost the mercury pool will lie in the bottom of the tube and over the wires 45, 46 as shown in Fig. 7. In any other position, however, the mercury pool will lie in the enlarged portions of the tube 40 away from one or both of the wires 45, 46; and, therefore, the circuit of the lamp will remain open and the lamp cannot be operated until it is put into a position in which no injury to the lamp will occur. If the construction of the lamp (e. g., the heat transfer capacity of the sleeve 23), should be such as to require that one end be always uppermost when the lamp is burned in vertical position, the wires 45—46 may be made shorter so as to fall short of the mercury pool in the opposite end of the tube 40.

In order to avoid arcing between the electrodes, the tube 40 is preferably filled with a fluid in addition to the mercury which has a high breakdown voltage and is, therefore, adapted to quench any arc which might tend to form between the mercury and the contact wires 45, 46.

We have already referred to the possibility of having the current lead to the further electrode pass along the outside rather than the inside of the tube 15. This we have illustrated in Fig. 5 in which the strip 50 made of metal sheeting, strip or wire is connected at one end to the lead wire 17b sealed through the upper end of the tube 15b and is brought back along the outside surface of the tube. Strip 50 in this case, like the wire 13 in the case of Figs. 1 and 2, serves as a capacity member and a magnetic repulsion means, as well as to lead the current to the outer electrode. In order to increase the capacity effect and to bring it as close as possible to the wall of the tube, a conductive layer 51 is deposited directly on the surface of the tube. This may be, for example, a layer of graphite deposited as a water suspension of graphite, e. g., such as is commonly known as aquadag, or a chemically and/or electrically deposited metal, or a strip of metal leaf or foil may be used so as to provide a high reflecting surface, thereby avoiding loss of light efficiency which might occur to some extent with the graphite. Also the exterior strip, acting at the same time as a reflector, can consist of silver, or chromium, or chromium plated metal. The quality of absorbing and holding radiant energy as heat is an advantage of the graphite layer when used on the pole vessel for the layer 22.

It is an advantage of this extended layer in

intimate contact with the surface of the glass that it reduces the danger of injury to the glass by electrolysis or puncturing when a starting potential is imposed upon the glass while still very hot. Such danger might exist if only the relatively heavy lead connection 50 were in actual contact with the glass of the tube, since it could contact only at occasional points along its length, and in that case the electrical charge would be concentrated at the points of contact instead of being distributed, as in the case of the capacitative layer applied directly and in intimate contact on the surface of the glass.

If the current lead is returned outside of the tube in this way, it may advantageously be insulated, e. g., by enameling or by use of a glass jacket or otherwise. The base connection sleeve 23 may, of course, be similarly insulated.

The lamp shown in Fig. 8 is similar in construction and operation to that shown in Fig. 1, with certain obvious exceptions. In this case instead of mounting the tube 15c directly upon the connector base 25c, a protective jacket 23c is provided in which the tube 15c is mounted by means of the spring 36 and the resilient twisted wires 37. The connecting wire 32c between the connector base 25c and the lead-in wire 14c to the lower electrode 11c serves also to hold the inner tube 15c in position within the jacket 23c.

In this case the electrodes 11c are in the form of shallow cups of refractory metal nested or filled with wire mesh or otherwise provided with interstices into which the activation material is filled. The lead wire 13c for the upper electrode is connected to the strip 50c brought back on the outside of the envelope 15c instead of inside as in the case shown in Fig. 1.

This application is a continuation-in-part of applicants' prior application Serial Number 643,502, filed November 19, 1932, and now Patent Number 2,092,363, granted September 7, 1937.

We claim:

1. An electrical discharge device which comprises a sealed tube permeable to radiation of the discharge, a filling therein adapted to carry a luminous electrical discharge, electrodes positioned at opposite ends of the tube at least one of which is an activated electrode adapted to be heated to a glowing temperature by action of the discharge itself, electrode support wires sealed through the tube at the same end thereof beyond the electrode, the longer of said wires extending along the path of the discharge near the side of the tube and to the electrode at the opposite end of the tube, an insulating tube on said longer support wire adapted to insulate it from the discharge and the other electrode, a connector base having contact members connected to said electrode support wires, a tubular member extending between said tube and the base adapted to restrict heat transfer therebetween and forming a substantially rigid mechanical connection between the tube and the base, the tubular connection member comprising a metallic sleeve around the end of the tube electrically connected to one of the electrode support wires, and the device further including a conductive layer on the surface of the tube beneath said metallic sleeve and electrically connected to the other electrode support wire, and a layer of insulating material between said conductive layer and said sleeve whereby to provide a capacity in parallel with the discharge to facilitate starting.

2. In an electrical discharge device a sealed

tube, a filling in the tube adapted to provide a gaseous pressure at operating temperature sufficiently high so that the discharge takes the form of an intense luminous cord constricted from the wall of the tube, electrodes positioned at opposite ends of the tube at least one of which is an activated electrode adapted to be heated to arcing temperature by the discharge, lead-in wires for the electrodes sealed through one end of the tube beyond one of said electrodes including a shorter wire connected to the nearer electrode and a single longer wire extended near the wall of the tube to the opposite electrode and an insulating tube on said longer wire adapted to insulate it from the discharge and the nearer electrode, and said electrodes being positioned so that the portions thereof from which the discharge emanates are eccentric within the tube, the support wire passing along the opposite side of the tube.

3. In an electrical discharge device a sealed tube, a filling in the tube adapted to provide a gaseous pressure at operating temperature sufficiently high so that the discharge takes the form of an intense luminous cord constricted from the wall of the tube, electrodes positioned at opposite ends of the tube at least one of which is an activated electrode adapted to be heated to arcing temperature by the discharge, lead-in wires for the electrodes sealed through one end of the tube beyond one of said electrodes including a shorter wire connected to the nearer electrode and a single longer wire extended near the wall of the tube to the opposite electrode and an insulating tube on said longer wire adapted to insulate it from the discharge and the nearer electrode, and said electrodes being positioned so that the portions thereof from which the discharge emanates are eccentric within the tube, the support wire passing along the opposite side of the tube.

4. In an electrical discharge device of the type having a sealed tube, electrodes positioned at opposite ends thereof, at least one of which is an activated electrode adapted to be heated to glowing temperature by action of the discharge itself, and filling material adapted to provide a gaseous atmosphere for the discharge, the combination therewith of a capacity member on at least one end of the tube, connected to one of the electrodes and comprising a conductive layer substantially covering the end of the tube surrounding an electrode, which combination further includes a connector base and the capacity member includes a metal mounting by which the discharge tube is secured to the connector base.

5. In an electrical discharge device of the type having a sealed tube, electrodes positioned at opposite ends thereof, at least one of which is an activated electrode adapted to be heated to glowing temperature by action of the discharge itself, filling material adapted to provide a gaseous atmosphere for the discharge, and means for supplying current to the discharge adapted to raise the tube to a temperature at which it is capable of injury by a voltage less than the maximum available from the current supplying means when no current is flowing, the combination therewith of a solid current carrying member electrically connected to one of said

electrodes and substantially in contact with the outside of said sealed tube, and a conductive film in substantially complete contact with the surface of said tube beneath said current carrying member, whereby to distribute the charge of said current carrying member over a substantial area and avoid concentration thereof at points of contact between the tube and said member.

6. In an electrical discharge device of the type having a sealed tube, electrodes positioned at opposite ends thereof and filling material in the tube adapted to provide a gaseous atmosphere for the discharge and comprising a vaporizable material the vapor pressure of which affects the nature of the discharge in the device and which requires the maintenance of a high super-atmospheric temperature for the intended operation of the device the combination therewith of a connector base and mounting means secured to the base at one end and engaging the sealed tube at a substantial distance from said base and adapted to support said tube from the base and to restrict heat transfer between said tube and the base, said mounting means comprising a metal sleeve crimped over one end of the sealed tube and having a circumferential series of holes therein between the base and the tube adapted to restrict heat transfer between said base and tube.

7. In an electrical discharge device of the type having a sealed tube, electrodes positioned at opposite ends thereof and filling material in the tube adapted to provide a gaseous atmosphere for the discharge and comprising a vaporizable material the vapor pressure of which affects the nature of the discharge in the device and which requires the maintenance of a high super-atmospheric temperature for the intended operation of the device the combination therewith of a connector base and mounting means secured to the base at one end and engaging the sealed tube at a substantial distance from said base and adapted to support said tube from the base and to restrict heat transfer between said tube and the base, said mounting means comprising a tubular member secured at one end to the connector base and surrounding the end of the sealed tube, means between the tubular member and said sealed tube for holding the tube spaced from the tubular member, and means between the tube and the tubular member for intercepting heat transfer from the tube to said mounting.

8. In an electrical discharge device of the type having a sealed tube, electrodes positioned at opposite ends thereof and filling material in the tube adapted to provide a gaseous atmosphere for the discharge and comprising a vaporizable material the vapor pressure of which affects the nature of the discharge in the device and which requires the maintenance of a high super-atmospheric temperature for the intended operation of the device the combination therewith of a connector base and mounting means secured to the base at one end and engaging the sealed tube at a substantial distance from said base and adapted to support said tube from the base and to restrict heat transfer between said tube and the base, said mounting means comprising a tubular member secured at one end to the connector base and surrounding the end of the sealed tube, a layer of thermal insulation material between the tube and the tubular mounting member, and a heat reflecting layer between said tube and said thermal insulation material.

9. A high pressure arc discharge lamp designed for operation from a source of current of predetermined potential and current capacity which operates with an intense luminous cord constricted with respect to the cross-sectional area of the envelope, and which has a tubular glass envelope permeable to at least part of the radiation from the discharge, a filling of vaporizable material adapted to provide during normal operation a gaseous atmosphere for the arc at high pressure adapted to give said constricted cord, solid electrodes at least one of which is activated, having limited area on which the arc may strike, whereby substantially to fix the position of the arc, which is characterized by the positioning of said electrodes eccentrically of said envelope and the proportioning of the envelope so that, when operating from said current source in horizontal position with said limited arcing areas of the electrodes below the axis of the tube the arc cord will not impinge against the uppermost wall, and when operating vertically on said current source the arc cord will not impinge against the opposite wall.
10. An arc discharge device comprising a sealed tube, electrodes spaced apart in said tube and a filling therein adapted to provide a discharge carrying atmosphere of pressure sufficiently high to give a constricted luminous cord discharge substantially narrower than the inside diameter of the tube, means for supplying current for the discharge sufficient to cause injury to a wall of the tube if the discharge cord burns too close to said wall and means for conducting the entire current for the discharge along said wall in a direction opposite to its flow in the discharge, whereby to repel the discharge from said wall by the opposed electro-magnetic effects of the current flowing in opposite directions through the arc and said conducting means respectively, said electrodes being positioned with the arc-carrying portions thereof eccentrically in said tube on the opposite side of its axis from said current conducting means, and the tube being so shaped and dimensioned that when it is positioned vertically with the arc burning therein from said current source the wall opposite said current conducting means is substantially spaced from the luminous cord of the discharge.
11. An electrical discharge device comprising a source of alternating current, a sealed tube, a filling in said tube of material adapted to provide a gaseous atmosphere for the discharge, electrodes positioned at opposite ends of the tube, means for conducting the discharge current to the electrodes, a capacity between the electrodes including a conductive member secured to said tube in capacitative relation to the current conducting means to one electrode and connected to the electrode, an inductance in series between said current source and said current conducting means which with said capacity is not resonant to the frequency of the alternating current source, additional capacity adapted when connected into the circuit with said electrodes, said first-named capacity and said inductance to produce resonance, and means for connecting said second-named capacity into the circuit for starting and disconnecting it therefrom when the discharge has started.

12. An electrical discharge device comprising a source of current, a sealed tube, a filling in said tube of material adapted to provide a gaseous atmosphere for the discharge electrodes positioned at opposite ends of the tube, means for

conducting the discharge current to the electrodes, a capacity in parallel across said electrodes, and a ballasting impedance in series with the electrodes, the capacity and the impedance being proportioned to give relaxation oscillations and resonance to a frequency produced by the oscillations.

13. An electrical discharge device comprising a source of current, a sealed tube, a filling in said tube of material adapted to provide a gaseous atmosphere for the discharge, principal electrodes positioned at opposite ends of the tube, an auxiliary electrode near to one electrode so as to provide a shorter discharge path and connected into the discharge circuit through an impedance so that the discharge therefrom will be short circuited by a discharge between the principal electrodes when the discharge is established in the path between the principal electrodes, means for conducting the discharge current to the electrodes, a capacity in parallel across said discharge paths, electrodes, and ballasting impedance in series with said discharge paths, the capacity and the impedance being proportioned to give relaxation oscillations with the auxiliary discharge and resonance to some frequency produced by the oscillations, whereby to establish the discharge between the principal electrodes.

14. A device as defined in claim 13 in which the current source is an alternating current source, the impedance is an inductance, and the circuit is in resonance at a higher harmonic of the frequency of the alternating current from said source which harmonic is produced by the relaxation oscillation.

15. An electric gaseous discharge device comprising a tubular sealed envelope having a vaporizable material therein, a plurality of inleads sealed into one end of said envelope and supporting electrodes therein, a sleeve secured to said end of said envelope and enclosing said inleads, and a base secured to said sleeve and connected to said inleads, said sleeve including an intermediate portion between the base and end of the lamp of lesser heat conductivity than the base and the remainder of the sleeve to maintain the end of the envelope at a temperature sufficient to prevent condensation of said vaporizable material thereon.

16. An arc discharge device comprising a source of limited current from the discharge, a sealed tube, electrodes spaced apart in said tube, and a filling therein adapted to provide a discharge carrying atmosphere of pressure suf-

ficiently high to produce a constricted luminous cord discharge substantially narrower than the inside diameter of the tube, said current source supplying sufficient current for the discharge to cause injury to a wall of the tube if the discharge cord shifts its position too close to said wall and a conductor for the current to one electrode which extends along said wall of the tube beside the discharge path whereby to hold the discharge away from the tube by the opposed electro-magnetic effects of the current flowing in opposite directions through the arc and said conductor respectively, the current source, the distance between the electrodes and the distance from the wall subject to injury, measured midway between the electrodes, to the axis connecting the parts of said electrodes on which the arc strikes being proportioned respectively so that said distance between the axis and the part of the wall subject to injury is greater than the distance between the electrodes divided by the amperage of the current derived from said current source.

17. An arc discharge device comprising a source of limited current from the discharge, a sealed tube, electrodes spaced apart in said tube, and a filling therein adapted to provide a discharge carrying atmosphere of pressure sufficiently high to produce a constricted luminous cord discharge substantially narrower than the inside diameter of the tube, said current source supplying sufficient current for the discharge to cause injury to a wall of the tube if the discharge cord shifts its position too close to said wall and a conductor for the current to one electrode which extends along said wall of the tube beside the discharge path whereby to hold the discharge away from the tube by the opposed electro-magnetic effects of the current flowing in opposite directions through the arc and said conductor respectively, the current source, the distance between the electrodes and the distance from the wall subject to injury, measured midway between the electrodes, to the axis connecting the parts of said electrodes on which the arc strikes being proportioned respectively so that said distance between the axis and the part of the wall subject to injury is greater than the distance between the electrodes divided by the amperage of the current derived from said current source.
